UNITED STATES PATENT OFFICE.

LOUIS C. KRUMMEL, OF CLINTON, CONNECTICUT.

HEAD FOR BOTTLE-CAPPING MACHINES.

938,325.

Specification of Letters Patent. Patented Oct. 26, 1909.

Application filed January 29, 1909. Serial No. 475,006.

To all whom it may concern:

Be it known that I, LOUIS C. KRUMMEL, a citizen of the United States, residing at Clinton, in the county of Middlesex, State 5 of Connecticut, have invented certain new and useful Improvements in Heads for Bottle-Capping Machines, of which the following is a description, reference being had to the accompanying drawing, and to the figures of reference marked thereon.

The invention relates to machines for capping bottles, and more especially to that class of machines in which the metal cap is placed on the mouth of the bottle, and the flange of 15 the cap is turned underneath the shoulder at the mouth of the bottle, thereby securing the cap to said bottle.

An object of the invention is to provide a head for a machine of the above character, 20 which head shall be durable in construction and efficient in operation.

A further object of the invention is to provide a bottle-capping head with means for securing the cap to the bottle, which means 25 includes devices for limiting the movements of the parts, so that undue or breaking pressure will not be applied to the mouth of the bottle, during the closing of the cap.

A further object of the invention is to provide a bottle-capping head which includes a cap-receiving chuck, movable longitudinally 30 independently of the head.

A further object of the invention is to provide a bottle-capping head with a cap-receiving chuck and with an ejector; for forcing the capped bottle out of the chuck.

A further object of the invention is to provide a bottle-capping head having a chuck which is movable longitudinally in the head, 40 and a cap ejector, which head is so positioned relative to the cap-holding devices that the ejector and chuck serve to steady the cap and hold the same on the bottle until properly received by the head.

These and other objects will in part be 45 obvious, and will in part be hereinafter more fully described.

In the drawings, which show by way of 50 illustration one embodiment of the invention,—Figure 1 is a sectional view through my improved head; also showing its relation to a cap-holding device; Fig. 2 is a sectional view on the line 2—2, of Fig. 1; Fig. 3 is a sectional view of certain parts of the head, 55 showing the head expanded, that is, with the

inner sleeve moved to its extreme position out of the outer sleeve; Fig. 4 is a side elevation of the head; Fig. 5 is a sectional detail, showing a modified form of the invention in that the ejector is positively operated. Fig. 6 is a view similar to Fig. 1, showing a modified form of chuck support. Fig. 7 is a detail of the housing for the springs. Fig. 8 is a view on the line 8—8 of Fig. 7; and Fig. 9 is a detail view of the 60 65 chuck-operating device.

The entire head 1, as herein shown, is carried by a spindle 2, which may be the spindle of any suitable bottle capping machine, or of any other machine that will give the 70 head a rapid rotary motion.

In Fig. 1, the bottle-capping head is shown as rotating above a cap-holding device 3, which cap-holding device may be a part of any suitable automatic cap-feeding mechanism. It will be obvious, however, that from certain aspects of the invention, the bottle-capping head may be used without any cap-feeding device, the caps being 75 placed by hand on the bottle, which is inserted into the capping head.

My improved capping head comprises an outer sleeve 4, which is threaded on to the spindle 2. Said outer sleeve is recessed to receive an inner sleeve 5, which is connected to the outer sleeve by a spline 6, so that the inner sleeve may move into and out of the outer sleeve, but will rotate with the outer sleeve.

A spring 7 is located in a cut out or recessed portion 8 of the spindle 2, and at one end bears against the spindle, while at its other end said spring bears against the inner sleeve. The spring 7 will normally hold the inner sleeve in the position shown 90 in Fig. 3, that is, withdrawn from the outer sleeve, until the shoulder 9 engages the cap plate 10 carried by the outer sleeve. In this position the head may be said to be expanded.

The inner sleeve is provided with a central recess in which is mounted a chuck 11. The chuck is threaded on to a sleeve 12. The sleeve 12 extends through a collar 13, which is threaded into the inner sleeve 5. The inner sleeve is provided with a shoulder 14 and a ball bearing 15 rests on the shoulder 14, and is engaged at its upper side by the collar 13. The collar 13 is also provided with a reduced portion 16, which extends 105 110

down into the ball bearing 15. The reduced portion 16 terminates a short distance above the lower side of the ball bearing.

The chuck 11 slides freely in the inner sleeve 5, and remains stationary during the capping operation, while the inner sleeve rotates about the same. When the chuck is in its innermost position, as shown in Fig. 1, it engages the ball bearing, which takes the 10 end thrust caused by the forcing of the bottle up into the capping head. The sleeve 12 which carries the chuck 11, is provided with an enlarged head 17, which engages the upper face of the collar 13, and limits the downward movement of the chuck relative to the inner sleeve. A spring 18 engages the sleeve 12 at one end, and a collar 19 at the other end, and operates to normally hold the chuck in the position shown in Fig. 3, that is, with the enlarged head 17 of the sleeve 12 against the upper face of the collar 13.

The chuck 11 is provided with a bottle-cap-receiving recess 20, which is constructed 25 so as to conform to the shape of the cap being secured to the bottle. The chuck is also provided with a further recess to receive an ejector pad 21, carried by a stem 22, extending up through a central opening in the 30 chuck, and which is provided with an enlarged head 23 at its upper end, which engages a shoulder 24 formed in the central recess of the chuck, so as to limit the downward movement of the ejector pad. An 35 ejector rod 25 extends centrally through said head, and through the supporting spindle 2. The collar 19 above referred to, is carried by said ejector rod. The ejector rod at its lower end has a reduced portion 26, having 40 a rounded end normally bearing against the upper enlarged end 23 of the stem 22. A spring 27 surrounds the reduced portion 26 of the ejector rod, and bears at one end against the shoulder on the ejector rod, and 45 at the other end against the head 23 of the stem 22.

The collar 13, which bears against the upper face of the ball bearing 15, may be adjusted, owing to its threaded connection 50 with the inner sleeve. As a means for holding said collar in its adjusted position, I have provided the collar with a plurality of semicircular recesses 28. The inner sleeve has also a similar semicircular recess 29. The collar 13 is turned until one of the 55 recesses is brought opposite the semicircular recess 29, after which a screw or pin 30 may be inserted, to hold the collar 13 against accidental movement in the sleeve.

60 The closing roller 31 is herein shown as a corrugated crimping roller, although it is obvious from certain aspects of the invention, that said roller might be a smooth surface roller for spinning the material of the 65 cap underneath the flange on the bottle.

The crimping roller 31 is mounted to rotate freely on a stud 32, carried by a lever 33, pivotally supported by a rod 34, carried by the inner sleeve. The inner sleeve is recessed in order to provide a space for the 70 supporting lever 33. The outer sleeve has also a recess, in which is located a bar or plug 35, having at its upper end an enlarged head 36, and having its lower end rounded to engage a similar rounded socket in the 75 laterally projecting arm 37 of the lever 33. A spring 38 engages the upper end of the bar or plug 35. A screw is threaded into the upper part of the recess in the outer sleeve, and serves as an abutment for the 80 spring 38.

The ejector-operating rod 25 may be spring pressed or may be positively operated. In Fig. 5 of the drawing, I have shown a slightly modified form of construction of ejector-operating means. In this figure, the ejector head 40 is threaded directly on to the end of the ejector rod 41. The ejector rod extends up through the supporting spindle for the head, and at its upper 90 end is provided with a split nut and knuckle 42, which is pivoted to the lever 43.

In the operation of my device, the bottle is inserted up through the cap-supporting device, which carries a metal cap provided 95 with a packing, generally consisting of disks formed of a yielding material such as cork, which will not be affected by the contents of the bottle. The capping head, which is rotated continuously with the exception of the 100 ejector pad, the chuck and the ejector rod which are stationary, is located directly above the cap-supporting device, and the parts are normally in the position shown in full lines in Fig. 3, and in dotted lines in 105 Fig. 1. In this position it will be observed that the ejector pad is located directly above the cap, so that as soon as the bottle engages the cap and raises the same from its seat in the support for the cap, said cap 110 will be engaged by the ejector pad, and held on the mouth of the bottle, and properly directed into the receiving recess in the chuck. The chuck is also forced outward from the capping head, and lies in a position directly above the support for the cap. After the cap has been seated in the receiving recess of the chuck, a further upward movement of the bottle carries the 115 chuck and the ejector pad up into the inner sleeve, which, as the capping head is expanded, rests on the cap plate 10 of the outer sleeve. The crimping roller 31 is at this time, thrown back or to the right, as shown in Fig. 3, by reason of the fact that the inner sleeve is moved down out of the outer sleeve, carrying with it the supporting lever 33, and the arm 37 of the lever 33 has engaged the cap plate 10, which throws the crimping roller to the position stated. 120 125 130

A further upward movement of the bottle forces the inner sleeve up into the outer sleeve against the action of the spring 7. As the inner sleeve moves upward, the lever 5 carrying the crimping roller 31 also moves upward, and the arm 37 contacts with the plug or bar 35, which rotates the lever 33 about the supporting pin 34, and brings the crimping roller 31 into contact with the flange of the cap extending beneath the shoulder on the mouth of the bottle. Inasmuch as the head is continuously rotating, the crimping roller will be carried around the mouth of the bottle, which, together with the chuck and ejector pad, is stationary, thus gradually turning the flange of the cap underneath the shoulder on the bottle. When the inner sleeve contacts with the outer sleeve at its upper end, a further movement of the inner sleeve upward is prevented, and, therefore, the inward movement of the crimping wheel, that is, the movement of the crimping wheel into contact with the flange of the cap, is positively limited. This inner movement of the crimping wheel is also a yielding movement, for the reason that the plug or bar 35 may yield to the action of the spring 38. If, therefore, there should be an unevenness in the formation of the mouth of the bottle, so as to cause a breaking of the bottle, due to the excessive strain of the crimping wheel on the bottle, said crimping wheel would yield to allow the uneven portion of the bottle to be properly passed. It will be seen, therefore, that I have provided a device wherein the cap may be properly crimped and secured to the bottle, regardless of any uneven parts in the mouth of the bottle, and that the force with which the flange is turned underneath the shoulder on the mouth of the bottle may be adjusted by adjusting the screw 39, thus avoiding the breaking of the bottle.

After the cap has been secured to the bottle, the bottle is withdrawn from the crimping head, and the inner sleeve will first move out of the outer sleeve, after which the chuck will move out of the inner sleeve, and after the chuck and inner sleeve have reached the limit of their downward movement, the ejector pad will operate to force the capped bottle out of the recess in the chuck. The movement of the ejector pad downward, relative to the cap-supporting device is sufficient to force any broken portions of bottle down through the cap-supporting device, so as to prevent any clogging of the apparatus.

If the ejector pad is operated positively, as shown in Fig. 5, the cam for operating the same will, of course, be so timed as to bring about the movements above stated. That is, to allow the head to be expanded before the bottle is forced from the chuck.

In Fig. 6 the spindle 2, is a rotating spindle carrying the outer sleeve 4 and inner sleeve 5, which are of the same construction as that described in connection with Fig. 1, and the same reference numerals 70 have been applied to the parts thereof. The chuck 11 is threaded on to the end of a rod 44, which extends up through the rotating spindle 2. Said chuck is recessed to receive the ejector 23, which is held normally forced 75 out from the chuck by means of a suitable spring 45, located in a recess formed in the end of the rod 44, as shown in dotted lines in Fig. 6. The spring 7, which holds the crimping head expanded rests at its upper 80 end against a collar 46 which is secured to the spindle 2 by suitable pins 47. The rod 44 is threaded and provided with an adjustable threaded collar 48. A semi-cylindrical member 49, is provided with perforated projecting ends 50, which slide over the rod 44. Said member 49 fits the inner bore of the spindle 2. The collar 48 is cut away as at 51, so that said collar is formed with shoulders 52, which, when the opening in said 90 collar is in alignment with the openings in the enlarged ends 50, rest against the edges of the semicylindrical member 49. The collar 48 is adjustably secured to the rod 44, and by the shouldered connection 95 with the cylindrical member 49, said member is held from rotating with the spindle 2. A spring 53 surrounds the rod 44 and rests normally at its lower end against the lower enlarged head 50 of the cylindrical 100 member 49. A spring 54 also surrounds the rod 44 and is located between the upper face of the collar 48, and the upper enlarged end 50 of the semicylindrical member 49. In the operation of my device, the collar 48 is so 105 adjusted that when said collar rests upon the spring 53, the chuck 11 is positioned as shown in Fig. 6, that is, said chuck extends into the cap-feeding head, but is held at a sufficient distance above the ledge or shelf 110 supporting the caps, to permit said caps to be freely fed underneath said chucks. When a bottle is raised into contact with the cap, it is at once carried into the recess formed in the chuck moving the ejector 23 115 up into its recess compressing the spring 45. A further upward movement of the bottle causes the collar 48 to compress the spring 54, and allows the chuck 11 to engage a ball bearing support, to cause the inner sleeve 120 to move up into the outer sleeve in precisely the same manner as hereinbefore described. When the bottle is lowered after having been capped, the spring 54 will move the rod 44, and the chuck 11, downward 125 with the bottle. The collar 48 contacting with the spring 53, limits the downward movement of the rod 44 and the chuck, and holds the chuck in what may be called its normal position. An anti-friction washer 130

or ball bearing 55, supports the semicylindrical member 49, and allows the spindle to rotate freely about said member.

In order to remove any broken caps or broken pieces of caps from the capping head, I may provide my capping head with means for moving the chuck down into the capping head to a point below the ledge on which the caps normally rest, and thus positively force out of the capping head all said broken parts. As herein shown, the rod 44 is provided with a split collar 56, carrying pins 57, to which is pivotally connected a lever 58, fulcrumed at 59 upon any suitable support. A rod 60 having a collar 61 secured thereto, passes through an opening in an enlarged portion of the lever 58, and said rod may be given a downward movement at the proper time by a suitable cam. The parts are preferably so timed that as soon as the chuck reaches its normal position, that is, when the collar 48 rests on the spring 53, through the action of the expansion of the spring 54, the rod 60 is given a positive downward movement, thus forcing the chuck down into the capping head and compressing the spring 53. As soon as the chuck reaches its lower position, it should at once be released from the positive acting means, so that the spring 53 may return the same to its normal position slightly above the cap in the capping head, so as to allow the caps to be fed underneath the chuck.

If my device is applied to a machine wherein the same is stopped after each capping operation, the positive operation of the chuck should, of course, occur before the machine stops. By adjusting the rod 44 in the threaded collar 48, the normal position of the chuck may be varied.

Having thus described my invention, what I claim as new and desire to secure by Letters Patent, is:—

1. A bottle capping head including in combination, a rotatable member, a corrugated cap-closing roller carried thereby, a cap-receiving chuck supported by said rotatable member and movable longitudinally relative thereto.

50 2. A bottle capping head including in combination, a rotatable member, a corrugated cap-closing roller carried thereby, a cap-receiving chuck and an ejector for forcing the capped bottle out of said chuck.

55 3. A bottle capping head including in combination, an inner sleeve, an outer sleeve, means for expanding said head, a corrugated roller carried by said inner sleeve, a cap-receiving chuck, and an ejector for forcing the capped bottle out of said chuck.

60 4. A bottle capping head including in combination, an inner sleeve, an outer sleeve, means for expanding the head, a crimping roller carried by said inner sleeve, a chuck supported by said inner sleeve, about which

said inner sleeve may be rotated, and means whereby said chuck may be moved longitudinally of said inner sleeve.

5. A bottle capping head including in combination, a rotatable spindle, an outer sleeve carried thereby, an inner sleeve splined to said outer sleeve, a spring for forcing said inner sleeve out of the outer sleeve, means for limiting the movement of the inner sleeve relative to the outer sleeve, crimping means carried by said inner sleeve, a chuck supported by said inner sleeve and movable longitudinally relative to said inner sleeve.

6. A bottle capping head including in combination, a rotatable spindle, an outer sleeve carried thereby, an inner sleeve splined to said outer sleeve, a spring for forcing said inner sleeve out of the outer sleeve, means for limiting the movement of the inner sleeve relative to the outer sleeve, crimping means carried by said inner sleeve, a chuck supported by said inner sleeve and movable longitudinally relative to said inner sleeve, and an ejector for forcing the capped bottle out of the said chuck.

7. A bottle capping head including in combination, a rotatable member, a corrugated crimping roller carried thereby, and means for yieldingly pressing said flange-turning device into contact with the cap of the bottle.

8. A bottle capping head including in combination, a rotatable member, a flange-turning device carried thereby, means for yieldingly pressing said corrugated crimping roller into contact with the cap of the bottle, and means for limiting the inner position of the said flange-turning device.

9. A bottle capping head including in combination, a rotatable member, a corrugated crimping roller carried by said rotatable member, a cap-receiving chuck, means for yieldingly forcing the said crimping roller into contact with the flange on the cap.

10. A bottle-capping head including in combination, a rotatable member, a crimping roller carried by said rotatable member, a cap-receiving chuck, means for yieldingly forcing the said corrugated crimping roller into contact with the flange on the cap, and means for limiting the inner movement of the crimping roller.

11. A bottle-capping head including in combination, a rotatable member, a cap-receiving chuck, a lever pivoted to said rotatable member, a corrugated crimping roller carried by said lever, yielding means engaging said lever for forcing the corrugated crimping roller into contact with the flange, and means for adjusting said yielding means, whereby the pressure of the roller on the flange may be varied.

12. A bottle-capping head including in

combination, an inner sleeve, an outer sleeve, a cap-receiving chuck, a crimping roller, a lever supporting said crimping roller, means for supporting said lever by said inner sleeve, and yielding means carried by said outer sleeve for forcing said roller into contact with the cap.

13. A bottle-capping head including in combination, an inner sleeve, a cap-receiving chuck, a ball bearing for limiting the upward movement of said chuck, a threaded collar for engaging and supporting the ball bearing, a crimping roller carried by said inner sleeve, and means for forcing the said crimping roller into contact with the flange of the cap.

14. A bottle-capping head including in combination, an inner sleeve, a cap-receiving chuck, a ball bearing for limiting the upward movement of said chuck, a threaded collar for engaging and supporting the ball bearing, said collar having a plurality of semicircular recesses coöperating with a semicircular recess in the sleeve, whereby said collar may be locked in various adjusted positions by means of a pin fitting the semicircular recesses in the sleeve and collar.

15. A bottle-capping head including in combination, an inner sleeve, an outer sleeve splined to said inner sleeve, a cap plate carried by said outer sleeve for limiting the outward movement of said inner sleeve, a spring for forcing the said inner sleeve out of the outer sleeve, a chuck supported by said inner sleeve, a crimping roller carried by said inner sleeve, and means carried by said outer sleeve for swinging said crimping roller into contact with the flange of the cap.

16. A bottle-capping head including in combination, an inner sleeve, an outer sleeve splined to said inner sleeve, a spindle to which said outer sleeve is threaded, said spindle having a recessed portion, a spring located in the recessed portion of said spindle and bearing against said inner sleeve, means for limiting the outward movement of said inner sleeve, a bottle-receiving chuck supported by said inner sleeve, a crimping roller carried by said inner sleeve, and means carried by said outer sleeve for swinging said crimping roller into contact with the cap.

17. A bottle-capping head including in combination, an inner sleeve, an outer sleeve splined to said inner sleeve, a spindle to which said outer sleeve is threaded, said spindle having a recessed portion, a spring located in the recessed portion of said spindle and bearing against said inner sleeve, means for limiting the outward movement of said inner sleeve, a bottle-receiving chuck supported by said inner sleeve, a crimping roller carried by said inner sleeve, means carried by said outer sleeve for swinging

said crimping roller into contact with the cap, an ejector, and means for operating the same to force the capped bottle out of said chuck.

18. A bottle-capping head including in combination, an inner sleeve, a crimping roller, a lever pivoted to said inner sleeve and supporting said roller, an outer sleeve, a spring-pressed bar carried by said outer sleeve and engaging said lever, and means for adjusting the tension on said spring.

19. A bottle capping apparatus including in combination, a crimping head, a crimping roller carried thereby, a cap receiving chuck supported by said head, a cap supporting member, and means whereby said chuck may be moved into and out of said cap supporting member.

20. A bottle capping apparatus including in combination, a crimping head, a crimping roller carried thereby, a cap receiving chuck supported by said head, a cap supporting member, means for normally supporting said chuck at a point adjacent the cap supporting member, and means whereby said chuck may be moved into said cap supporting member.

21. A bottle capping apparatus, including in combination a crimping head, a crimping roller carried thereby, a chuck supported by said head, a cap supporting member, a spring for normally supporting said chuck, at a point adjacent the cap supporting member, and means whereby said chuck may be positively moved into said cap supporting member, to clear the same of obstructions.

22. A bottle capping head including in combination, a chuck, a rod carrying said chuck, a spring for forcing said chuck from the head, a spring for forcing said chuck into said head, the tension on said springs being so proportioned as to hold said chuck normally slightly extended from said head.

23. A bottle capping head including in combination a chuck, a rod supporting said chuck, a collar carried by said rod, springs carried by said rod, and engaging the opposite sides of said collar.

24. A bottle capping head, including in combination, a rotatable spindle, a crimping roller rotating with said spindle, a chuck, a rod supporting said chuck, and extending through said spindle, a collar carried by said rod, springs engaging the opposite sides of said collar, a semi-cylindrical member, located between said springs and said spindle, and held by said collar from rotating with the spindle.

In testimony whereof I affix my signature, in presence of two witnesses.

LOUIS C. KRUMMEL.
